UNITED STATES PATENT OFFICE.

WALTER HADDON, OF LONDON, ENGLAND.

ELECTRIC ACCUMULATOR CASING.

Application filed January 15, 1926, Serial No. 81,575, and in Great Britain January 19, 1925.

This invention relates to, and has for its object the provision of improvements in, electric accumulator casings.

The invention resides in the arrangement 5 according to which while there is a ventilation or sweating hole for the gas in the closure of the casing, any of the acid which may well or splash to the outside of said closure tends to run back to the interior of said 10 casing.

One embodiment of the invention is illustrated in the accompanying drawings and the same will now be described, it being understood that the particular construction 15 illustrated is susceptible of various modifications without departing from the scope of the invention as defined in the appended claim.

In these drawings:—

20 Figure 1 is a side elevation of an accumulator casing and closure therefor.

Figure 2 is a section on line A—A of Figure 1.

25 Figure 2^a is a part sectional view of a modification.

Figure 3 is a plan with closure removed.

Figure 4 is a plan of the closure.

In these drawings the casing 1 and the closure 2 (from the latter of which the 30 accumulator plates may be supported) are both made of lead or lead alloys and the closure 2 is adapted to rest on a horizontal ledge 3 formed around the interior of the casing at such a distance below the rim 35 thereof that when the closure is in situ the said rim of the casing extends to a level above the upper surface of the closure.

This arrangement has the advantage inter alia that by providing a recess 7 in the wall 40 of the container or casing 1 and a packing ring 8 carried in a co-operating recess 9 in the closure 2 a leak-proof joint is formed when the closure is applied and pushed down on to the ledge 3. This arrangement is 45 shown in Figure 2^a. The closure furthermore is provided with a filling hole in which a closing plug 4 is adapted to screw, and the upper end of this filling hole terminates in an enlarged concave recess 5 formed in the 50 upper side of the closure. Finally the closing plug 4 is formed with a ventilation or sweating hole 6 which comes out sideways at a level a little above the level of the surface of the closure.

From the above it will be seen that, should 55 any of the accumulator acid splash or well to the outer side of the closure it will be prevented from spilling by the rim of the casing (which as aforesaid extends above the upper surface of the closure) and will tend 60 to run back into the casing either by gravitating into the enlarged recess 5 and thence draining through the screw threads of the closing plug or else by draining between the 65 contacting surfaces of the closure and the casing.

With regard to the construction of this embodiment the casing and the closure consist each of one integral lead casting, and for constructional convenience and also for purposes of economy the thickness of these castings is maintained small and largely constant throughout. Thus the ledge 3 around the interior of the casing is formed as shown by the whole portion of the walls above said ledge being outwardly set with respect to the remainder of said walls and similarly the enlarged recess 5 at the upper side of the closure is formed by a bodily downward displacement of the material of the closure. 70

The closure moreover is formed with 75 downwardly extending vertical flanges 2^a which rest on the aforesaid ledge 3. The closing plug 4, moreover, is preferably 80 dished at its inner end.

85 What I claim and desire to secure by Letters Patent is:—

In combination, an accumulator casing proper formed with an interior horizontal ledge, a cover formed with a filling hole 90 adapted to rest on said ledge, and a plug, formed with a vent hole, adapted to fit removably in said filling hole, the upper surface of said cover being below the upper edge of said casing proper, said filling hole 95 at its upper end being expanded so as to provide a sunken annular clearance around said plug and, at its lower end, being adapted to provide a sufficiently inexact fit with said plug to permit of the draining back of acid 100 from said upper surface of said cover, and said vent hole coming out above said upper surface of said cover so that acid cannot drain back through said vent hole.

In witness whereof I affix my signature.

WALTER HADDON.
